UNITED STATES PATENT OFFICE.

SAMUEL B. WILLIAMS, JR., OF BROOKLYN, NEW YORK, ASSIGNOR TO WESTERN ELECTRIC COMPANY, INCORPORATED, OF NEW YORK, N. Y., A CORPORATION OF NEW YORK.

AUTOMATIC TELEPHONE SYSTEM.

1,247,771.

Specification of Letters Patent.

Patented Nov. 27, 1917.

Application filed January 31, 1916. Serial No. 75,329.

To all whom it may concern:

Be it known that I, SAMUEL B. WILLIAMS, Jr., a citizen of the United States, residing at Brooklyn, in the county of Kings and 5 State of New York, have invented certain new and useful Improvements in Automatic Telephone Systems, of which the following is a full, clear, concise, and exact description.

10 This invention relates to automatic telephone systems, and particularly to systems of the type in which the act of initiating a call causes the finding switch mechanism to seek and establish connection with the terminals of the calling line. The invention has particularly to do with a system of this 15 sort in which the switch mechanism first selects a group in which the calling line is located, and then finds the particular line in 20 that group that is calling.

One of the objects of the invention is to prevent a single line finding mechanism from searching for and establishing connection with two lines in different groups at the 25 same time, when calls in different groups are initiated simultaneously, or practically simultaneously. In the particular embodiment in which the invention is illustrated, the finding switch is of the multiple brush 30 type, that is, of the type in which the movable element is provided with a plurality of brushes, one for each of the groups of lines served by the switch. The brushes are normally held in position not to engage their 35 respective stationary terminals, and one or another brush, or set of brushes, is tripped and made operative, depending upon the group in which the line that is to be engaged is located.

40 In automatic telephone systems of the type to which this invention relates, it is the practice to provide a plurality of extension circuits terminating upon line finder switches, all of which have access to the 45 same group or groups of lines, so that the calling line may have its connection extended through the medium of any one of the finder switches that is not in use at the time. One of the objects of this invention is 50 to provide an organization in which the initiation of a call causes one, and only one, of the plurality of idle finder switches to become active to extend the connection of the calling line. When a subscriber calls, one 55 of the finder switches that is not in use is

made active through the medium of a starting circuit common to the finder switches and to the lines that they serve, and makes connection with the calling line. In its movement the finder switch that is selected places another finder switch in readiness to respond to the next call that is initiated. The calling condition of the line, which results in the starting of the finder switch persists until the finder switch has connected with the calling line, which may be some time subsequent to the time when the next finder switch in order has been placed in operative relation with the starting circuit. To prevent the continuation of this calling condition of the line from causing the starting of the next finder switch in order, the system is so organized that the calling line is deprived of control over the starting circuit from the time the next finder switch has 75 been placed in readiness until the started switch finds and alters the starting condition of the calling line.

Another object of the invention is to prevent the lines of any one group, where more than one group of lines has access to the finder circuit mechanism, from having undue preference in their control over the finder circuits, and thus tending to monopolize their use. In the embodiment of the invention here illustrated, the lines served in common by several finder switches are divided into groups, these groups being so related to the starting and group selecting circuits of the finder switches that only one 90 group at a time has access to them. The arrangement is such, however, that the lines of other groups have access to the finder switch controlling circuits as soon as the finder switch first selected is started and another finder switch is placed in readiness; while the lines in the group in which the calling line is located, are cut off from access to the starting circuit for a somewhat longer interval, an interval long enough to 100 permit the selected finder switch to find the calling line. As a result, other calls originating in the group in which the first call originated, are able to secure the services of a finder switch only after calls that may in 105 the meanwhile have originated in other groups, have had an opportunity to be served.

Another object of the invention resides in the provision of means whereby, when a call 110

- is initiated on one of the lines served by a group of finder switches, a tripping device will be actuated which is arranged to release any of the brushes of said switches which have access to the calling line terminals and which are in normal position. Heretofore, in systems of this type, a tripping device has been employed for each switch, and it has been necessary to operate this device during a preliminary selecting movement of the switch in order to select and render operative the desired set of brushes. In the present system the tripping devices are common to all the switches of a group, one tripping device being provided for all the brush sets having access to the same section of the panel bank. The particular tripping device for releasing the desired set of brushes is operated prior to the actuation of the switch. This allows selection to take place rapidly without the relatively long preliminary brush-selecting movement required by previous systems of this type.

25 A preferred embodiment of the invention, in which the above-mentioned and other novel features are realized, is disclosed in the accompanying drawings, in which Figure 1 is a side elevation with parts broken away of a switch having a common trip rod, and
30 of a type suitable for employment in connection with this invention; Fig. 2 is a perspective view of a portion of the trip rod together with the trip and restoring levers of a pair of brush controlling devices; and
35 Figs. 3, 4 and 5, taken together, with Fig. 3 at the left and Fig. 5 at the right of Fig. 4, show the circuit organization.

As the switch shown in this system, with the exception of the common trip feature employed in this invention, may be the same as that disclosed in Patent No. 1,123,696, to Craft & Reynolds, issued January 5, 1915, only so much of the switch will be described in detail as is particularly concerned with the novel features herein disclosed, reference being had to said patent for an understanding of the remainder of the switch structure.

Referring to Figs. 1 and 2, 1 represents a finder switch shaft which may be moved longitudinally in either direction by means of the extension 2 thereof, being caused to engage one or the other of two constantly and oppositely rotating power members. To move the shaft up, the extension 2 is brought into engagement with the power member 3 by means of the idler pulley 4, operated by the clutch magnet 5; and to move the shaft down, the extension 2 is brought into engagement with the power member 3' by means of the idler pulley 4', operated by the clutch magnet 45.

Secured to the shaft 1 is a plurality of sets 6, 6' of brushes. These sets are usually 65 ten in number and corresponding brushes

thereof are multiply connected. Each set 6, 6' of the brushes is adapted to traverse a section 7, 7' of a panel bank of stationary contacts. The brushes of each set 6, 6' are normally maintained in inoperative position by being spaced apart or separated by means of a brush controlling device 8, located between the innermost brushes of the set. This controlling device 8 is adapted to be rotated to release the brushes and allow them to approach each other so as to engage the contacts in the panel bank. Secured to each controlling device 8, are a trip lever 9 and a restoring lever 10.

Extending transversely to the shafts 1 of 80 a group of switches are a plurality of rotatably mounted trip rods 11, one for each set of brushes on any one of the switches. These trip rods 11 extend parallel to the plane of the shafts 1 of the switches of the group, 85 and are normally positioned just below the restoring levers 10 of the brush sets when they are in their normal positions. Rotatably secured to the rods 11 are a series of yoke or U-shaped members 12, one being 90 provided for, and adapted to be brought into operative relation with each of the trip levers 9 adjacent thereto (see Fig. 2). Springs 13, each having one end secured to the rod 11 and the other end to one of the yokes, 95 tend to force the yokes in a clockwise direction, which movement, however, is limited by means of the stops 14 fixed to the rod.

Secured to each of the rods 11, near one end thereof, is a crank member 15 which is secured to the armature 16 of the trip magnet 17 by means of a link 18. Upon the energization of the magnet 17 and the attraction of its armature 16, a corresponding rod 11 will be caused to rotate in a clockwise direction, as viewed in Fig. 2. This will place the yokes 12 thereof above or in operative relation to the trip levers 9 of all the switches of the group which are then in normal position. If, now, one of the switches be caused to move upwardly, the brush controlling device will be rotated so as to release the set of brushes corresponding to the operated trip rod.

Referring now to the circuit organization illustrated in Figs. 3, 4 and 5, this is shown to consist of two subscribers' lines extending from their respective stations A and B to multiple stationary contact terminals on a panel type switch which comprises a plurality of line finders of which only two, S and S', are shown. The two switches S and S' form the line-finding terminals of two connecting or trunk circuits F and F'. The telephone line from the station A is represented as extending to multiple terminals in one group, and the telephone line from station B as extending to multiple terminals in another group of the line terminal groups served by the two 130

finder switches S and S'. The apparatus common to the group of lines that includes the line extending to station A, is represented at G in Fig. 3, and the apparatus 5 common to the group of lines that includes the line extending to station B is represented at G' in Fig. 3. The group apparatus of still another group is shown at G² in Fig. 3. At the bottom of Fig. 3 there is 10 shown at C certain apparatus common to all of the groups of lines, and which serves to distribute or allot the calls to idle finder switches.

The group apparatus of each group of 15 lines is controlled through the medium of apparatus individual to each of the various lines of the corresponding group. Any group apparatus, in operating, acts through the medium of the apparatus common to 20 the groups to start an idle finder switch that has been pre-selected by the common apparatus. It also acts to trip the set of brushes corresponding to the group in which the calling line is located, and to prevent 25 the tripping of another set of brushes through the medium of the group apparatus of another group of lines. As indicated at the right-hand side of Fig. 5, each of the 30 finder circuits is provided with means for extending the circuit of the calling line to other circuits through which the calling line may be connected with the wanted line.

It is thought that a description of the 35 manner in which the system operates will make clear the organization and inter-relation of the elements of which the system consists. Let it be assumed that the subscriber at station A desires connection with some other subscriber, and takes his telephone from its hook. The closing of the 40 circuit at station A energizes the subscriber's line relay 51 and also the relay 50 common to the group, over a circuit that extends from battery through the relays 50 and 51 45 in series, and thence to station A over one side of the line and back to ground at the central office over the other side of the line; the circuit at the central office passing through normally closed contacts of the cut-off relay 52. The group relays 53 and 54 50 of the associated group G, as well as the corresponding trip magnet 17, are all connected in parallel from battery to the front contact of the group relay 50, the armature of this 55 relay being connected with ground at 86 through normally closed contacts of the relays 53, 53', and 53² of the respective groups G, G', and G². Consequently when the relay 50 is energized by the taking of 60 the telephone at station A, it closes an initial energizing circuit for the group relays 53 and 54 and the trip magnet 17. The closure of this energizing circuit by the relay 50 is subject, however, to the non-operated condition of the relay 55 of the

associated group and the relays 53¹ and 53² of the other groups G' and G² through which the energizing circuits extends to ground at 86.

The conditions under which the closure of 70 the initial energizing circuit may be prevented by the operated condition of any one of these relays, will hereinafter be described. For the present it will be assumed that these relays are inert, and that the 75 relays 53 and 54 of group G and the associated trip magnet 17 are operated by relay 50 in closing its contacts. Relay 54 in operating closes in its upper contacts an energizing path for itself, relay 53 and trip magnet 17, which path extends directly to ground by way of resting contacts of the relay 56 common to the group. Trip magnet 17 in operating rotates the trip rod 11 to bring all of the yokes 12 into position to 80 release the corresponding group brushes of whichever finder switch is started. Relay 53 in operating interrupts, in its right-hand resting contacts 63 and 64, the path to ground 86 over which the initial energization of the group relays and trip magnets of the other groups G' and G² is effected. At the same time its outer left-hand armature applies ground to a conductor 57 common to all of the groups. 85

The application of ground to the conductor 57 causes the starting of an idle finder switch, the particular one started being determined by the position of the allotter switch which, with its controlling relays 106 and 107, is illustrated at C in Fig. 3. The allotter in the present instance consists of an ordinary sequence switch 100 with its associated cams or commutating disks 101, 102, 103, 104 and 105. The sequence switch 105 is shown merely diagrammatically and may be of the type disclosed in Patent 1,127,808 issued February 9, 1915, to Reynolds and Baldwin. Contact 101 is open when the sequence switch is in the positions indicated 100 by the numerals adjacent to said contact, and closed between these positions. The numerals adjacent to the other contacts indicate the only positions of the switch in which the contacts are closed. 110

Assuming that the sequence switch on allotter 100 is at rest in position 1, when the relay 53 operates to apply ground to conductor 57 a circuit is closed from ground by way of conductor 57, allotter contact 103 (1), conductor 58, sequence switch contact 202 (1) and motor magnet of sequence switch 200 of the finder circuit F. This sequence switch 200 and the sequence switch 200' of finder circuit F' may also be of the type disclosed in the patent to Reynolds and Baldwin heretofore mentioned; the numerals applied to the contacts 201 and 201' respectively of the two switches indicating positions in which these contacts are opened, 120 125 130

while the numerals applied to the other contacts of the two switches indicate the positions in which the associated contacts are closed.

- 5 The closure of the circuit traced above by way of conductors 57 and 58 energizes the motor magnet of sequence switch 200 and causes that switch to move out of position 1 and into position 2. In position 2 sequence switch 200 closes at contact 211 a circuit that energizes the up-drive magnet 5 of the associated finder switch S, this circuit extending from battery through magnet 5 and by way of conductor 31 to sequence switch contact 211 (2) and thence to ground by way of the resting contacts of relay 220. The energization of the up-drive magnet 5 starts the upward movement of the brushes of finder switch S.
- 10 An instant after the upward movement starts, the tripping levers 9, of all the sets of brushes of the switch, reach the position where they are adapted to be engaged and tilted by one or another of the tripping 25 yokes 12, depending upon which of the group trip magnets is at the time energized. As substation A is assumed to be calling, the trip magnet 17 is operated, and therefore the brushes 41 of the started finder switch S are 30 tripped and made operative.

As the brush carrying rod 1 of the switch S moves past the position where the set of brushes is tripped, the grounded brush 43 at the top of the rod comes into engagement 35 with the commutator segment 44, thus grounding the conductor 46 which extends to sequence switch contact 205; and as the sequence switch is at the time in position 2, the circuit is completed by way of contact 40 205 (2), conductor 60 and allotter sequence switch contact 105 (1) to the right-hand resting contacts of relay 106 (Fig. 3), and thence by way of the winding of relay 106 and sequence switch contact 102 (1) to battery. This causes the relay 106 to break this 45 circuit and apply ground directly by way of its right-hand armature, this ground maintaining the relay 106 energized until its circuit is broken in sequence switch contact 102 by the moving of allotter sequence switch 100 out of position 1 in which it has been resting.

It will be remembered that when station A called, relay 54 of group G in operating 55 applied a ground by way of its upper armature and the resting contacts of group relay 56 to hold relays 53 and 54 and trip magnet 17 energized independently of the initial energizing path by way of the series contacts of relays 53 to ground 86. When relay 54 operated, it connected in its lower contacts, the lower winding of relay 55 with conductor 61. The initial energization of relay 55 is therefore dependent upon the 60 application of ground to conductor 61, and 65

this is effected when commutator segment 44 of finder switch S, is engaged by brush 43 at the end of the group selecting operation, to energize relay 106 of the common group C, in the manner already described. 70

Thus when the grounding of commutator segment 44 marks the completion of the group selecting operation, the energization of relay 55 of group G is effected initially by way of the ground at commutator segment 44, then by way of the ground applied in the right-hand armature of relay 106 when that relay operates and finally by the closure of a locking circuit by way of its upper winding, its upper alternate contacts, 75 the upper closed contacts of relay 54 and the resting contacts of relay 56 to ground. Thereafter, the maintained energization of relays 54 and 55 is subject to the control of relay 56; relays 54 and 55 becoming inert 80 when relay 56 is energized.

Relay 55 in operating breaks the path to ground, over which the relay 53 and the trip magnet 17 had theretofore been held operated, and permits both to become inert. 90 Furthermore, as long as relay 55 remains locked up, it holds open the circuit between the contacts of the group relay 50 and the energizing windings of the relay 53 and the trip magnet 17, so that as long as relay 55 95 remains operated, neither the calling line from station A nor any other line of the associated group can exercise any control over the relay 53 and the corresponding trip magnet 17. But when relay 53 is deenergized by the energization of relay 55, it again closes the inter-group series circuit in its right-hand resting contacts so that the relays 53 and trip magnets of other groups 100 may be operated by the initiation of calls in those groups. The reciprocal control 105 exercised by the various groups over each other will be particularly described hereinafter.

Under the conditions assumed, relays 54 110 and 55 of group G are now locked up awaiting the energization of relay 56, the sequence switch 200 of finder circuit F is in position 2, and the brushes of finder switch 2 corresponding with the group in which 115 line A is located, are released and moving up over the terminals of the lines of that group. In position 2 of sequence switch 200, a testing circuit is completed from battery through test relay 220, sequence switch contact 206 (2 to 3), conductor 47 and test brush 36 to the test conductors 23 of the various lines of the group which the test brush engages in passing. The conductors 23 of all of the lines of the group, excepting the line that is initiating the call, are open in the contacts of their respective line relays 51. As the line relay 51 of the line from station A is energized, the associated test conductor 23 is closed in the contacts 120 125 130

of this relay, and consequently when test brush 36 engages the terminals of the line of station A, a circuit for test relay 220 of finder circuit F is completed to ground by way of test conductor 23, front contacts of line relay 51 and winding of group relay 56. The completion of this circuit operates relays 220 and 56. Relay 56 in operating opens the locking circuit of the associated group relays 54 and 55, restoring the group circuit to normal and again giving the lines of the group control over relay 53 and trip magnet 17 through the medium of relay 50. Relay 220 in operating opens in its back contact the energizing circuit of the up-drive magnet 5, thus stopping the upward movement of the switch brushes, and closes in its front contacts an energizing circuit for the motor magnet of sequence switch 200, by way of sequence switch contacts 202 (2), thus moving the sequence switch out of position 2.

Immediately upon moving out of position 2, sequence switch 200 closes a circuit that operates the cut-off relay 52 of the line of calling station A. This circuit may be traced from battery through resistance coil 221, sequence switch contacts 210 (2½ to 4), conductor 48, brush 41, conductor 42 and winding of cut-off relay 52 to ground. Cut-off relay 52 in operating disconnects group relay 50 and line relay 51 from the line of calling station A, and both of these relays thereupon release their armatures. To insure the opening of the group initial energizing circuit in the contacts of relay 50, before it is reestablished in the contacts of relay 55, relay 55 is made slow to release—as by placing a copper sleeve about its core and applying only a weak retractile force to its armatures.

At the right in Fig. 5, at E and E', are shown the terminals of the finder circuits. These terminals diagrammatically represent contacts of a switching device of any desired character, either manual or mechanical. When the calling line is found, the sequence switch 200 moves out of position 2, as above explained, and is carried by its governing contact 201 to position 4, where it remains until the finder circuit is joined to the next link in the talking circuit, by the terminals E being connected with contacts, as those indicated adjacent thereto. When this occurs, contact 223 will be closed in any desired and obvious manner, completing a circuit from battery through relay 225, contact 207 (4), lower terminal E and contact 223 to ground. Relay 225 is energized and completes a circuit from battery through the motor magnet of sequence switch 200, contact 224 (4) and front contact and armature of relay 225, thus moving the sequence switch 200 to position 5. The calling line is now extended to the ter-

minals E by contacts 208 and 209. In position 4 the upper and lower contacts of sequence switch spring 210 are closed. When the terminals E unite with the contacts of the extension circuit, battery is supplied to the third from the top contact of said circuit, and through the third from the top terminal E to the contact 210 (4 and 5), thus insuring that the cutoff relay 52 will remain energized when battery is removed from its circuit at upper contact 210, when the sequence switch moves to position 5.

The circuit condition described above is that which exists while the subscribers are talking. At the end of the conversation the hanging up of the telephone at station A brings about the opening of contact 223 in any desired and obvious manner, and this in turn opens the circuit of relay 225. The armature of the last mentioned relay in falling back, applies ground for energizing the motor magnet of sequence switch 200 by way of sequence switch contacts 202 (5). This moves the sequence switch out of position 5 and into position 6. In position 6 of the sequence switch an energizing circuit is completed for the down-drive magnet 45 by way of sequence switch contacts 204 (6); and just before the brushes of finder switch S reach their normal position, commutator segment 39 is engaged by the grounded brush 43', thus closing a circuit from battery through the motor magnet of sequence switch 200, contacts 202 (6), conductor 38, segment 39, and brush 43' to ground. This moves the sequence switch 200 from position 6 to its normal position.

The system is so organized that as soon as one of finder circuits is appropriated by a calling line and its finder switch is started and passes the group selecting stage of its operation, another finder switch and circuit are placed in readiness to take the next call. This is accomplished in the following manner: As has already been described, immediately after the brushes have been tripped, the movement of the finder switch causes the grounding of segment 44 of the commutator, and the ground thus applied operates relay 106 of the common group C and relay 55 of the particular group G in which the calling line is located. Relay 106 in operating closes in its left-hand contact a circuit for energizing the motor magnet of allotter sequence switch 100. The instant sequence switch 100 starts to move, it opens in its contact 102 (1) the energizing circuit of the relay 106. That relay therefore is but momentarily operated, being energized by the impulse of current from the passing contact of grounded brush 43 with commutator segment 44, and immediately upon energization acting to start sequence switch 100 and thereby to break its own energizing circuit in contacts 102 (1) of the sequence 130

switch. Sequence switch 100, as a result of the momentary operation of relay 106, moves into position 2, where the energizing circuit for its motor magnet, by way of sequence switch contacts 101, is again opened. Sequence switch contacts 103, 104 and 105 in each resting position of the sequence switch extend the three conductors which they control to a different set of conductors 58, 59 and 60, each set of conductors extending to a different finder circuit.

When the allotter sequence switch 100 stood in position 1, the circuits controlled by it were extended to finder circuit F. In moving to position 2 upon the starting of the finder switch of finder circuit F, the circuits controlled by the allotter are extended by way of switch contacts 103, 104 and 105 and conductors 58', 59' and 60' to finder circuit F'. Assuming in the first place that the finder circuit F' is not in use, its sequence switch 200' is in position 1, and consequently all three of the conductors 58', 59' and 60' are open in their respective contacts of sequence switch 200'. This being the case, allotter sequence switch 100 rests in position 2 until the initiation of the next call applies ground to conductor 57 of the starting circuit, whereupon sequence switch 200' of finder circuit F' is moved into position 2, the associated finder switch S' is started, and the grounding of commutator segment 44 of finder switch S' operates relay 106 and causes the allotter sequence switch 100 to be moved out of position 2 in which it is resting, in a manner similar to that already described in detail.

If the finder circuit F' is in use, its sequence switch is in a position from 3 to 18 inclusive. Now when the allotter sequence switch 100 moves from position 1 to position 2, it completes a circuit from battery through lower contacts 102 (2), winding and right-hand resting contacts of relay 107, contacts 104 (2), conductor 59' and sequence switch contact 204' (3 to 18) to ground. Consequently relay 107 operates to close, in its left-hand contacts, an energizing circuit for the motor magnet of allotter switch 100, and the switch is moved through position 2. In like manner the allotter is moved through the positions corresponding with finder circuits that are busy, and whose sequence switch contacts 204 are therefore in positions 3 to 18, and stops in the first encountered position corresponding with a finder circuit that is idle. When such a finder circuit is encountered, the allotter holds that circuit in operative relation with the group circuits to take the next call that is initiated.

In order to explain the inter-relation existing between the group circuits that prevents the tripping of two or more sets of brushes upon a started finder switch, it may be assumed that stations A and B initiate

calls simultaneously. Under this assumption relay 50 of group G and relay 50' of group G' are energized and close their contacts at the same instant. As previously described, when the relay 50 operates, it tends to close a circuit for the associated relays 53 and 54 and the corresponding trip magnet 17. This circuit includes conductor 62 which extends serially through resting contacts of the relays 53 of all the groups to ground at 86. In like manner relay 50' of group G' tends to close a similar circuit for the associated relays 53' and 54' and the corresponding trip magnet 17', which circuit also includes conductor 62 that extends serially through the resting contact of the relays 53 of the different groups. Consequently, when any of the group relays 53, 53' or 53' is operated far enough to interrupt its right-hand resting contacts, it thereby interrupts the initial energizing circuit for the relays and trip magnet of any other group.

As relay 50 of group G and relay 50' of group G' are assumed to be energized and to close their contacts simultaneously, for an instant each completes the initial energizing circuit of its associated relays and trip magnet by way of conductor 62, and relays 53 and 53' both start to pull up. But at the outset of the attractive movement relay 53 opens its contacts 63 and thus interrupts the initial energizing path of relay 53' to ground 86 by way of conductor 62. As contact 64 of relay 53' has not opened at this stage of the operation, the initial energizing circuit of relay 53 by way of conductor 62 is maintained, and the continued flow of current causes relay 53 to bring about the full attraction of its armatures. Contact 64 of relay 53 is broken toward the end of the attractive movement; but before this happens, the inner left-hand contacts of relay 53 are closed, thus providing an energizing path for relay 53 independent of its contacts 64. As long as relay 53 remains operated it holds the energizing path 62 for the other groups open in its contacts 63 and 64, and therefore, although relay 50' is held operated by calling subscriber B, it is ineffective to cause the operation of the associated relays 53' and 54' and the corresponding trip magnet 17'. This is also true with respect to any relay 50 that may be operated as the result of a call in any other group. As the trip magnet and the relays 53 and 54 of each group operate together over the same energizing circuit, the arrangement described prevents more than a single trip magnet being operated at a time and insures that only a single set of brushes on the finder switch will be brought into operative relation with its associated line terminals.

If it had happened that station B had called an instant ahead of station A, then

the corresponding relay 53 of group G', in operating and opening its contacts 64', would have interrupted the conductor 62 upon which relay 53 of group G depends for 5 its operation; and therefore the closure of the contacts of relay 50, as a result of the calling of station A, would not be effective to close an energizing path for the associated relays 53 and 54 and the corresponding trip magnet 17. Thus in all cases the operation of more than one tripping device is prevented.

To prevent a premature closing of the contacts of the relays 54 of the various group 15 circuits on the closure of the initial energizing circuit and at other times, these relays are preferably of a type which makes them slow to close their contacts as a result of their energization. This characteristic may 20 be given them in any well-known manner, as by providing their cores with copper sheaths and giving their armatures or switch springs a relatively strong retractile tendency. To procure the best results in the operation of the system, the relays 54 should be relatively slow and the relays 53 relatively quick in operating; while the relays 55, as heretofore pointed out, should be relatively quick in operating and slow in releasing. Also it is desirable that the allotter sequence switch 100 should move its contacts quickly upon the energization of its motor magnet.

The system is so organized that although 35 the finder circuits are placed in readiness to respond to calls in rapid succession, and in less time than is required for a started finder switch to find and connect with the terminals of a calling line, the continuance of the 40 calling condition of a line after a finder switch is started and another placed in readiness, will not cause the starting of the second finder switch. This is accomplished by so-organizing the system that the impulse 45 of current which is produced by the started finder switch at the completion of the group selecting operation, not only causes the allotter to place another finder circuit in readiness, but also deprives the calling line of further control over the starting circuit. 50 In other words, as has heretofore been described, the grounding of the commutator segment 44 at the completion of the group selecting operation of the finder switch, not 55 only advances the allotter 100 to bring another finder circuit into operative relation with the group circuit, but also energizes the group relay 55 to cut off the associated group relay 53 and trip magnet 17 from control by the relay 50, and to keep the relay 53 and magnet 17 disconnected from relay 50 until the relay 56 is energized to release relay 55 at the finding of the calling line and the consequent release of relay 50. The 60 circuit operations whereby this result is ac-

complished have heretofore been described in detail.

Another result accomplished by the organization described above is that for a time after each group has had access to the starting circuit and to the control of its corresponding group trip magnet, some other group has the preference in controlling the starting circuit and the trip magnet associated with that group. Thus the operation 70 of the relay 55, which releases the associated relay 53 and tripping device 17 and renders them irresponsible to the control of the associated relay 50 until after the calling line is found, also, in the releasing of relay 53, 80 restores the initial series energizing path 62 for the groups and renders it possible for any other group to operate its group relay 53 and trip magnet 17 and thus avail itself 85 of the services of the other finder switch and circuit which the allotter has placed in readiness. Therefore if, for instance, two calls are initiated in group G and one call in group G' simultaneously, relay 53 and trip magnet 17 of group G will be operated 90 to start and trip the brushes of the waiting finder switch, after which group G will be deprived of control over its relay 53 and magnet 17 until the first in order of the two 95 calling lines in group G is found. But the first started finder switch at the conclusion 100 of its group selecting movement acts through the allotter 100 to place another finder switch in readiness; and as relay 55 of group G, in operating to deprive the lines 105 of its associated group of control over the associated trip magnet and the common starting circuit, releases relay 53 to restore the control of the other groups, the call that is waiting in group G' starts the second 110 finder switch and operates magnet 17' to trip the corresponding group brushes. When the second started finder switch acts through the allotter 100 to place a third finder switch in readiness and restore the control of the 115 other groups over the starting and tripping circuits, and when the finding of one of the calling lines in group G releases relay 55 and again makes relay 50 effective to control its associated relay 53 and trip magnet 120 17, then the third finder switch is started to take the second of the two calls originated in group G. Thus it is impossible for a number of calls initiated practically simultaneously in one group, to monopolize the 125 services of the finder switches, as after each use of the starting and tripping circuits by one group, the calls of other groups are given control over these circuits in preference to calls waiting in the same group.

What is claimed is:

1. The combination with a plurality of lines, of a plurality of finder switches for making connection therewith, a starting circuit adapted when actuated to start one of

said finder switches, means actuated at the outset of movement of said started switch to place another switch under the control of said starting circuit, means under the control 5 of each of said lines in calling for actuating said starting circuit, and means actuated by said started switch for temporarily preventing a second actuation of said starting circuit by said calling line, whereby the starting 10 of two finder switches by one call is prevented.

2. The combination with a plurality of lines divided into groups, of a plurality of finder switches for making connection therewith, a starting circuit for said finder switches, line-controlled means for each group of lines adapted to effect the energization 15 of said starting circuit to start a finder switch, and means actuated in the starting 20 of said switch to render the line-controlled means of said group temporarily ineffective and to place another finder switch under the control of said other groups.

3. The combination with a plurality of lines divided into groups, a plurality of finder switches for making connection therewith, starting means for starting said switches consecutively, a group selecting device common to said switches for each group 30 of lines, means actuated upon the initiation of a call for operating said starting means and the selecting device of the group in which the calling line is located, and switching mechanism controlled in the movement 35 of the started finder switch for rendering said means thereafter temporarily irresponsible to a call in the same group.

4. In a telephone system, the combination with a multiple brush line finder, of electro-magnetic tripping devices, one for each brush, an energizing circuit for each of said devices, means for closing each energizing circuit, means actuated in the closure of any of said energizing circuits for rendering the

other circuits inoperative, means controlled 45 in the movement of the line finder for rendering the first mentioned circuit inoperative and said other circuits operative, and means actuated in the further movement of 50 said line finder for restoring said first mentioned circuit to operativeness.

5. In a telephone system, the combination with telephone lines arranged in groups, of a finder switch with which said telephone lines are connected, said switch being adapted for group and individual line selection, a device associated with each group of lines for controlling the group selecting operation of said switch with respect to the corresponding group of lines, said device being normally operable by the initiation of a call in any line of its associated group, means actuated in the operation of any of said devices for rendering the other devices inoperative by their associated lines, means actuated at the completion of the group selecting operation of said switch for rendering said other devices operable and the device of the calling line group inoperative, and means actuated upon the completion of the individual line selecting operation of said switch for rendering the device of the calling line group operable by its associated lines.

6. The combination with a plurality of lines divided into groups, of a plurality of finder switches for making connection therewith, means for moving said finder switches, means controlled by any line in calling for making one of said finder switches operative to connect therewith, and means adapted thereafter to deprive said calling line or any other line in the associated group of control over any finder switch until said line is found.

In witness whereof, I hereunto subscribe my name this 27th day of January, A. D. 1916.

SAMUEL B. WILLIAMS, JR.
